MAGNETRON DEVICE

Benjamin V. Valles, Williamsport, Pa., assignor to Litton Precision Products, Inc., San Carlos, Calif., a corporation of Delaware

Filed Apr. 2, 1969, Ser. No. 16,561

Term of patent 14 years

Int. Cl. D26—01

U.S. Cl. D26—8

FIG. 1 is a perspective view of a magnetron device showing my new design;

FIG. 2 is a side elevation thereof; the opposite side is substantially a mirror image of the side shown; and

FIG. 3 is a front elevation thereof; the undisclosed rear side is substantially a mirror image of the front side shown.

I claim:

The ornamental design for a magnetron device, substantially as shown as described.
